APPARATUS FOR EQUALIZED INDUCTION
HEATING OF WORKPIECES

Harold A. Strickland, Jr., Detroit, Mich., assignor,
by mesne assignments, to The Ohio Crankshaft
Company, Cleveland, Ohio, a corporation of
Ohio.

Application April 12, 1945, Serial No. 587,986

5 Claims. (Cl. 219—13)

1

This invention relates to the heating by inductive means of irregularly shaped workpieces.

In furnaces where the heating is by induction of electrical energy, the usual practice is to provide a heating coil uniform in its heating effect throughout its length so that a workpiece inserted within the chamber is uniformly heated. A furnace of this type is generally satisfactory where the workpiece is uniform in shape, for example, cylindrical, but where the workpiece is not uniformly shaped as, for example, where the diameter of the central section of the workpiece is less than the diameter of the ends, this type of furnace may not be satisfactory as it may produce overheating of the central section.

A primary object of the present invention is to provide apparatus and circuit arrangements which may be utilized in connection with a heating coil to modify the energy available for heating along the length of the heating coil so as to conform to variations in the substance of the workpiece along the axis of the heating coil.

Still another object of the invention is to provide effective adjusting means for the energy output of a heating coil along its length which may be applied to usual existing furnace types without difficulty.

An object also is to provide energy adjusting means which may readily utilize alternative apparatus to accomplish the desired results.

Further objects will appear on consideration of the apparatus and circuit of an embodiment of the invention hereinbelow set forth and illustrated in the accompanying drawing, in which:

Figure 1 is an elevation of an induction heating coil unit with the control unit connected therewith;

Figure 2 is a diagrammatic showing of inductive means for controlling the energy flow along the coil axis;

Figure 3 shows a workpiece of irregular shape.

Referring to Figure 1, there is shown in outline an induction furnace 1 which includes the usual heating coil 2 of uniformly dimensioned and spaced turns surrounding a heating chamber 3. The heating coil is externally and internally lined with fire-proof insulation layers 4 and 5 and the furnace chamber is lined with fire-brick 6 supported by tubular cooling rails 7. These rails are provided with support lugs 8 for holding the workpiece 9 in position within the chamber.

The coil is provided with a plurality of taps 10 which extend outwardly at the side of the furnace. The furnace coil and accessory parts are supported on asbestos composition end plates 11 and 12

as indicated. Alternating current is supplied from a source, preferably, of high frequency current.

In order to secure the variation in energy output of the induction heating coil for heating articles of irregular shape, I utilize a second coil generally indicated by the numeral 13 which is mounted directly above the furnace. This auxiliary unit comprises a single coil 14 provided with taps 15 and supported by end plates 16 and 17. Since both pairs of asbestos composition support plates 11—12 and 16—17 are square in shape, it is desirable that the lengths of the furnace coil and the auxiliary coil be the same so that the pairs of support plates may be mounted directly one upon the other as shown. Electrical connection is made between the two coils through the connectors 18 and 19 each of which is formed of a flat metal strip centrally apertured at one end and slotted at the other end so that the plate may be pivotally mounted on either the upper or lower taps and detachably connected to one or more of the taps in the other unit.

In operation, the main heating current is passed through the heating coil as between points 20 and 21 of Figure 2. The applied voltage and frequency may be constant in value so that a uniform heat supply is available for a uniformly dimensioned cylindrical workpiece. Should, however, an irregular workpiece such as shown in Figure 3 and in dotted outline in Figure 1, be placed in the furnace chamber, it becomes necessary to reduce the heat output in the section 22 of lesser diameter as opposed to sections 23 and 24 of full diameter. This is accomplished by connecting the upper ends of the connectors 18 and 19 to a selected length of inductor coil 14 and the lower ends of the connectors to taps opposite the ends of section 22 so that the portion of the heating coil which encloses section 22 of the workpiece and is operative for heating the same is bypassed by the parallel connection of inductor 13. This parallel connection effectively reduces the current flow in the furnace coil section opposite section 22 of the workpiece so that the heating effect is minimized to the point of safe and adequate temperature for the desired purposes.

As indicated in Figure 2 and by the taps 15 in Figure 1, the inductor 13 is variable so as to obtain variation in the impedance of the shunt circuit. By utilizing an inductor shunt instead of a resistor, the power loss is substantially reduced. A related advantage of the inductor shunt for the specified purpose lies in its employment as a flux return for the heater coil, the coil turns of the

inductor being wound so as to develop a flux flow counter to that of the furnace coil.

It is apparent that by the construction as described it is unnecessary either to vary the cross section of the heating coil or to vary the space factor of the coil turns in order to secure variation of heat energy as applied to an irregular work-piece. By the simple expedient of introducing an impedance in shunt with selected sections of the heating coil, without disturbing the main heating coil circuit, applicant is able to secure any desired variation of heat energy input to the work-piece and this may be accomplished readily without important modification of the standard heating coil arrangement.

The showing as made is diagrammatic and hence no limitation is implied thereby other than may be required by the scope of the claims hereto appended.

What is claimed is:

1. In combination, an electric induction heating coil wound in a single direction and having connections to an electric power source, said coil having a plurality of taps intermediate said connections and an inductance coil connected across at least a pair of said taps intermediate said connections, whereby to reduce the heating effect of the heating coil between the taps connected to said inductance coil.
2. The combination of claim 1 wherein said inductance coil has a variable inductance.

3. The combination of claim 1 wherein said inductance coil has a plurality of taps along its length adapted to be selectively connected to the taps of said heating coil.

4. The combination of claim 1 wherein the flux field of the inductance coil is opposite to the flux field of the heating coil and the inductance coil is positioned exteriorly of and adjacent to the heating coil whereby the flux fields may be additive.

5. The combination of claim 1 wherein said inductance coil is wound in an opposite direction to said heating coil and said coils are disposed in adjacent relationship with their axes substantially parallel.
